UNITED STATES PATENT OFFICE.

FRED K. ATHERTON AND CLARENCE F. WEBB, OF RACINE, WISCONSIN; SAID WEBB
ASSIGNOR OF HIS ENTIRE RIGHT TO CHRISTIAN P. PETERSEN, OF RACINE, WIS-
CONSIN.

BURGLAR ALARM.

1,421,144.

Specification of Letters Patent. Patented June 27, 1922.

Application filed October 31, 1921. Serial No. 511,607.

To all whom it may concern:

Be it known that we, FRED K. ATHERTON and CLARENCE F. WEBB, both citizens of the United States, and residents of Racine, in the county of Racine and State of Wisconsin, have invented certain new and useful Improvements in Burglar Alarms; and we do hereby declare that the following is a full, clear, and exact description thereof.

10 Our invention refers to a burglar alarm, and it has for its primary object to provide for a simple, economical and safe burglar alarm capable of being attached in juxtaposition to a window or door, whereby the 15 trigger may be tripped upon movement of the window or door, to thus release a spring controlled firing pin, whereby a cartridge is exploded.

Specific objections of our invention are to 20 produce, as a manufacturing product, a simple structure which can be put upon the market at the minimum price, and which will not readily be disarranged through rough usage.

25 Another object of our invention is to provide a burglar alarm, having a simple and economical means for locking the firing plunger against inadvertent tripping when the same is not set for use.

30 Another object of our invention is to provide a bracket and housing for the mechanism, whereby the same is protected and sealed, so as to prevent injury to the party setting or operating the same.

35 With the above and other minor objects in view, the invention consists in certain peculiarities of construction and combination of parts, as are hereinafter set forth, with reference to the accompanying drawings and 40 subsequently claimed.

In the drawings,

Figure 1 represents a plan view of a burglar alarm, embodying the features of my invention with parts broken away, and 45 other parts in section to more clearly illustrate the details of construction.

Figure 2, a side elevation of the same, partly in section, as indicated by line 2—2 of Figure 1.

50 Figure 3, an end view of the burglar alarm, the same being shown attached to a window sash, and in position to be tripped by movement of either one of the sashes, the said sashes being shown in section, and

55 Figure 4, a detailed cross section of the

burglar alarm, showing the safety locking mechanism, the section being indicated by line 4—4 of Figure 2.

Referring by characters to the drawings, 1 represents a bracket, having apertured feet 2, which feet are secured to the framework of a building in juxtaposition to a door, or, as shown in Figure 3, to one of the sash members A of a window. The bracket has projected therefrom, a centrally bored cartridge magazine 3, which magazine is aligned with apertured ears 4—4', that project from the bracket, the outer ear 4' being formed with a longitudinal slot 5 therein. The ears are provided for the support of a reciprocative and oscillatory firing plug 6, the end of which plug is adapted to exert an exploding force against the cap of a cartridge a, which is seated in the bore of the magazine 3. The firing plug has mounted thereon, a coil spring 7, the lower end of which engages a cotter pin 8, while the upper end engages the bottom face of the ear 4'. The outer end of the firing plug 6 is formed with a right angle extension, 75 constituting a trigger 7'. The firing plug is also provided with a locking pin 9, which pin is arranged to travel downwardly through the slot 5 of the lug 4', when the firing plug is released for action, the said 80 pin being locked by engagement with the end of the lug surface of the lug 4', when the firing plug is set preparatory to being tripped. In this position, the pin is at approximately 90° from the mouth of the 85 slot 5, and the slot 5, at its mouth, is curved, to permit the pin 9 to automatically seek its line of travel through the slot, when said pin has been rotated a predetermined distance, with relation to its axis of oscillation. 90

As best shown in Figures 1 and 3 of the drawings, the firing plunger has been oscillated to its cocked position, in which position the coil spring 7 is compressed and the safety pin 9, in said position, holds the 100 plunger preparatory to a tripping action. As shown in Figure 3, the trigger 7' is extended in the path of travel of a lower sash member B. Hence, should the window B be moved upwardly or the window A 105 downwardly, the trigger will be engaged and locked upon its bearings to a position that the pin 9 will ride upon the curved mouth of the slot, and coincident to this action, the spring will be free to cause the 110

plunger to shoot downwardly and explode the cartridge *a*.

When the firing plunger has been retracted to load the spring 7, and, in some cases, 5 for instance during the day, it is not desirable to have the burglar alarm set. Hence, 10 a safety locking mechanism is provided. This locking mechanism comprises a transversely disposed stem 10, which stem is journaled in suitable apertures formed in the ear 4' of the bracket. The outer end of the stem is turned upwardly to form a setting handle 10', and the central portion of the stem, as best shown in Figure 4, is 15 provided with a tooth 11, which tooth is arranged to engage a similar notch 11', that is formed in the outer wall of the plunger 7. This notch is arranged to register with the setting stem tooth 11' when the plunger 20 is retracted to its loaded position, and hence, in this position, should it be desired to place the plunger "at safety," the setting handle is rotated approximately a quarter of a circle, whereby the tooth 11 will enter the 25 notch 11' of the plunger, and thus prevent action of the plunger irrespective of the position of the trigger. Hence it will be seen that, when this safety lock is manipulated, 30 the trigger, although rocked to a tripped position, will not function, due to the fact that it is held in its normal loaded position by the safety mechanism.

The entire mechanism is sealed and protected by a shell 12, which shell is fitted 35 over the bracket ears, as shown. The upper end of the shell is cut away slightly to clear the setting handle 10', and said shell at this point is folded backwardly to form a stop-flange to limit the setting movement of the 40 stem 10, whereby its tooth will accurately engage the plunger notch 11'.

Obviously, while we have shown and de-

scribed the burglar alarm as a fixture, in connection with the sliding sash frames, it is understood that the mechanism can be either 45 fastened to a door in such position that its trigger 7' will engage a fixed frame, or visa versa.

It is also understood that, while we have explained one exemplification of our invention in all of its details, the same may be varied within the scope of the claim, as understood by those skilled in the art.

We claim:

A burglar alarm for doors and windows, 55 comprising a bracket adapted to be attached in juxtaposition thereto, having a cartridge magazine extending from the bracket and spaced apertured ears extending therefrom, aligned with the cartridge magazine, one of 60 the ears being longitudinally slotted; the combination of a spring controlled firing plunger, having an offset trigger, the same being reciprocatively and oscillatorily mounted in the ear apertures, a setting pin 65 extending from the plunger arranged to engage one end of the slotted lug to hold the plunger in a firing position, and to be shifted for travel in the lug slot when said plunger is tripped, and a safety lock for the 70 plunger, including a manually controlled setting stem, rotatably mounted in the slotted bracket lug, the stem being provided with an offset setting handle, and a tooth 75 extending from the stem for engagement with the plunger notch when said plunger is retracted to its loaded position.

In testimony that we claim the foregoing we have hereunto set our hands at Milwaukee, in the county of Milwaukee and State 80 of Wisconsin.

FRED K. ATHERTON.
CLARENCE F. WEBB.
